UNITED STATES PATENT OFFICE

KENNETH W. DUNWODY, OF MACON, GEORGIA

BUILDING UNIT

Application filed June 6, 1929. Serial No. 368,872.

This invention relates to building units or bricks of hollow construction, and has for its object the provision of a brick of this type which is approximately twice the size of a standard solid brick and which, while presenting an exposed surface when laid in a wall having the quality and appearance of the best face brick, is interiorly provided with dead air spaces or voids of novel configuration and arrangement for heat insulating and fire proofing purposes.

The invention contemplates the provision of such a building unit, the header and stretcher walls of which are of approximately equal thickness, each stretcher wall being provided with a longitudinal series of vertically disposed openings, these openings being preferably, though not necessarily, cylindrical in shape. The central space bounded by the 20 stretcher and header walls is bridged by a pair of narrow, spaced, vertically disposed webs which are parallel to the stretcher wall and which divide this central space into three voids or dead air spaces, two wider ones between the perforated stretcher walls and the webs and a narrower one between the two webs. These voids together with the two series of openings in the stretcher walls form five dead air zones successively from one 30 stretcher face to the other. This arrangement greatly enhances the value of the unit as a fire proof and heat insulating building element, adapted to be used not only in ordinary building constructions, such as dwelling houses, schools, or office buildings, but in buildings where the heating or cooling costs are a big factor, such as garages, cold storage warehouses, refrigeration plants, or the like. The novel arrangement of the webs also provides a convenient hand hold means for the building unit.

One embodiment of the invention is described in the following specification and shown in the accompanying drawings by way of example.

Figure 1 is a perspective view of a portion of the wall of a building in which the novel building unit, which is the subject of the 50 present invention, is used, and in which is

illustrated a joist connection in which a halved unit is employed.

Figure 2 is a top plan view of the building unit; and

Figure 3 is an elevation partly in section 55 as seen from a header end of the unit.

The building unit or brick designated generally in the drawing by the reference numeral 10 is shown in Figure 2 as being flat and substantially square in plan and formed with 60 stretcher walls 11 and 12 have the faces 13 and header walls 14 and 15 having faces 16.

Longitudinally and centrally of each of the stretcher walls 11 and 12 is disposed a series of vertical cylindrical bores or openings 65 17. These openings 17 serve to lighten the construction of the brick, and provide keying means whereby the mortar may effectively form the bond between the bricks. Near the end of the header surfaces 16 of each unit 70 and in line with the series of holes 17 are the kerfs 18 which are shown here as semi-circular in cross-section but may be rectangular or of any suitable shape. These kerfs form bonding means for the joints between 75 two adjacent units in the same course.

The header walls 14 and 15 are connected near their middle portions by the two narrow, vertical parallel webs 19 and 20, which divide the central space enclosed by the 80 header and stretcher walls into three dead air spaces or voids, two wider ones 21 and 22 and the narrower centrally located space 23. The webs 19 and 20 are disposed in parallel 85 relation to the stretcher walls 11 and 12 and are of a convenient size and spacing to form means for grasping the brick with the hand, the thumb entering one of the spaces 21 or 22 and the fingers entering the other. By 90 having the webs 19 and 20 parallel to the length of the wall instead of transverse thereto the brick may be placed in position with a natural movement of the arm with the thumb toward the body and the fingers toward 95 the outer side of the wall. The ease with which the units are thus laid enables the mason to accomplish considerably more work without experiencing the fatigue which would result from handling and laying 100

units, the hand hold webs of which are disposed transversely to the length of the wall.

In Figure 1 is shown the partially constructed wall of a building in which this building unit is used. In laying a soldier course, either for the purpose of forming an ornamental belt course, sealing of the voids or air spaces, or for providing a course in which the joists 24 are set into the wall, the units 10 are arranged vertically with their stretcher faces 13 exposed as usual and their header faces within the wall. When laid in this position it will be noted that the kerfs 18 of the unit in this soldier course register with the series of openings 17 to form an effective keying means for the mortar joints.

In the arrangement shown in Figure 1 the joists 24 are set into the wall and a halved building unit placed at the end thereof. For this purpose and for use in turning corners the unit 10 may be readily severed along lines A—A in Figure 2 across the middle of the header walls and a half unit is obtained which is of very sturdy construction being bounded by the half header walls, one of the stretcher walls, and one of the webs 19 or 20. It is obvious that by the use of whole and half units it is possible to obtain any combination structure that may be obtained by the use of ordinary standard solid bricks, whether it be in an eight inch wall, a twelve inch wall, a chimney, a cornice, or other construction. It will also be readily understood that the unit may be made with any convenient dimensions for building walls of various thicknesses, thus, for instance, in a twelve inch wall the area of the unit may be 8" x 12" with the thickness either that of the standard brick, namely 2 1/4", or preferably slightly thicker to provide a more practical construction.

Having thus described the invention, what is claimed as new and desired to be secured by Letters Patent is:

- 45 1. A hollow building unit having relatively thick stretcher and header walls, said header walls being connected by a pair of vertical hand hold webs disposed in parallel relation to the stretcher walls, each of the stretcher walls being provided with a longitudinal series of vertical openings, the end openings of each series being intersected by the header face of said unit whereby a mortar key is provided near each end of the header faces.
- 50 2. A hollow building unit having relatively thick stretcher and header walls providing broad mortar receiving upper surfaces, said stretcher walls being provided with a longitudinal series of vertical openings, said header walls being connected at their middle portion by a pair of narrow, spaced, vertical hand hold webs disposed parallel to the stretcher walls, whereby there are provided five successive voids between the stretcher surfaces of the unit, and a mortar

key disposed near each end of the header faces.

In testimony whereof I hereunto affix my signature.
